UNITED STATES PATENT OFFICE.

FESSENDEN C. AMES AND HARRY L. MERRILL, OF NASHUA, NEW HAMPSHIRE,
ASSIGNORS TO ISAAC FRANK STEVENS, DOING BUSINESS AS MAINE MANUFACTURING COMPANY, AT NASHUA, NEW HAMPSHIRE.

REFRIGERATOR.

Application filed August 12, 1921. Serial No. 491,685.

To all whom it may concern:

Be it known that we, FESSENDEN C. AMES and HARRY L. MERRILL, both citizens of the United States, residing at Nashua, county of 5 Hillsborough, State of New Hampshire, have invented an Improvement in Refrigerators, of which the following description, in connection with the accompanying drawing, is a specification, like characters on the 10 drawing representing like parts.

This invention relates to a refrigerator provided with a sheet metal lining and to the construction both of the entire device and of the lining itself. The invention in 15 many of its features is not limited to the particular use to which the completed article may be put and is, therefore, not to be limited to refrigerators.

The object of the invention is particularly 20 to provide a sheet metal lining, preferably of a one-piece construction, which may be coated with enamel by an enameling process, requiring the application of intense heat. Refrigerators provided with a sheet metal lining coated with white enamel form a very 25 efficient and popular product, but there are many difficulties involved in the construction of such a product, and this invention is primarily designed to obviate these difficulties. 30 One object of the invention is to provide a simple and efficient means for clamping the metal lining to the framework of the cabinet, which is usually of wood, so that the edges of the lining can be drawn snugly 35 against the framework and without injury to the lining.

Another object of the invention is to provide means for properly supporting the plates of which the lining is made so that 40 they will not become distorted or thrown out of position when subjected to the intense heat of an enameling process.

These and other objects and features of the invention will appear more fully from 45 the accompanying description and drawings and will be particularly pointed out in the claims.

The drawings represent the invention embodied in a refrigerator of the ordinary 50 household type.

In the drawings:

Fig. 1 is a front elevation of a refrigerator cabinet with the doors of the food closets removed.

Fig. 2 is a view in horizontal cross section 55 of a refrigerator embodying a preferred form of the invention taken through the cabinet and lining on the line indicated at 2—2 of Fig. 4.

Fig. 3 is a detail in horizontal cross section 60 of the hollow post forming a part of the lining taken on the plane of the line 3—3 of Fig. 4.

Fig. 4 is a perspective view of the complete lining adapted for the cabinet shown 65 in Fig. 1.

Fig. 5 is a detail in vertical cross section taken on the line 5—5 of Fig. 2.

The lining, which is shown in perspective 70 in Fig. 4, is preferably made of metal plates welded or otherwise permanently secured together, and preferably into the L shaped form illustrated, thus providing the lining for the food closets and leaving the refrigeration or ice containing closet to be otherwise constructed in any suitable manner. The entire lining, with the exception of the clamping devices and shelf holding devices, as illustrated in Fig. 4, is subjected to an 75 enameling process requiring the application of intense heat through the entire device. Thus the interior surfaces of the lining are coated with the enameling compound fused or baked thereon, and usually white in color. This not only gives a pleasing effect to the 80 interior of the food closets but also produces a surface which may be readily cleansed and kept clean. Great difficulty is experienced, however, in maintaining the 85 shape and relation of the elements of the lining during the enameling operation owing to the intense heat, which tends to 90 warp and distort the elements.

The L shaped lining, shown as an embodiment of the invention, comprises a sheet 95 metal bottom plate 1 of rectangular form, provided with an aperture 2 for the waste pipe and along its front edge with a down turned flange 3. This flange acts to stiffen the front edge of the bottom plate throughout its entire length. A short side plate 4 extends upwardly at one side from and is welded to the bottom plate and a long side plate 5 extends up from the other side of the bottom plate and is welded thereto. These 100 side plates at their front edges are provided with the outwardly bent flanged portions 6 and 7, and preferably the plates in the rear 105

of the flanges 6 and 7 are bent to form the reentrant sections 8 and 9 respectively, so that the outer edges of the flanges 6 and 7 come about in line with the outer surfaces of the plates 4 and 5 respectively. These reentrant sections not only provide great rigidity and stiffness to the front edges of the side plates but they also enable the clamping devices hereinafter described to have a direct action.

A top plate 10 is welded to the top edge of the side plate 5 and extends laterally therefrom toward the middle. An intermediate partition plate 11 extends downwardly from the top plate with its body portion terminating in a flanged edge 12 well above the bottom plate 1, so as to provide ample space therebeneath for the circulation of air. This partition plate is also provided near the top with a suitable circulating aperture 13, this aperture being flanged at 14 at its lower or otherwise unsupported edge. At its front edge the partition plate is provided with a flange 15 and a reentrant front section 16 in the same manner as the side plates. This portion of the partition plate extends downwardly to the bottom plate in the construction illustrated.

An L shaped back plate 17 is welded to the rear edges of the top, bottom, side, and partition plates. The unsupported edge of this back plate 17 is flanged at 18 and the top edge of the side plate 4 is flanged at 19 to stiffen these edges. Thus it will be seen that the unsupported edges of the various plates are stiffened and strengthened by the flanged constructions illustrated, and the plates being welded or permanently secured together at their meeting edges there is thus produced a very firm and rigid structure. The lower front corner of the intermediate or partition plate 11 must be securely held in position or this plate will be distorted when heated. To prevent this result, this corner is rigidly connected to the bottom plate by a post construction. For this purpose the reentrant front section 16 and the flange 15 are carried down and welded to the bottom plate 1. Preferably this portion unites with an additional section of sheet metal 20 bent into an opposed form with an opposing front flange 21 to form a vertical hollow post, as illustrated. The edge of the section 20 abuts the rear edge of the depending section 16 and is welded thereto and the entire bottom edge of the post is welded to the bottom plate 1. This forms a very firm and rigid connection between the lower front corner of the plate 11 and the bottom plate, so that any danger of distortion of the plate 11 is prevented.

The bottom plate 1 is formed with an aperture 22 passing therethrough at the interior of the post, and preferably conform-

ing in shape to the bottom of the post. The front edge of the bottom plate 1, carrying the flange 3, is preferably carried forward a little of the plane of the flanges 6, 21, 15, and 7, so that this portion with the flange 70 at the front of the aperture is firm and rigid. Preferably also, the front portion of the post is left open longitudinally.

The aperture 22 prevents the bottom plate from being distorted in the vicinity of the post and the front opening of the post assists therein. The localization of the large amount of heat, due to the concentration of metal in the post where it connects with the bottom plate, is thus prevented by the aperture 22, which allows a free circulation of air at this important point.

The upper front corner of the side plate 4 is rigidly held in position during the enameling operation by a temporary brace 85 23 connected thereto and to the top of the post, and this brace is preferably removed after cooling and forms no part of the permanent structure.

The cabinet for the lining may be of any suitable form and construction but essentially comprises a front frame, herein shown as made of wood and secured to the sides 24 of the cabinet by screws 25. This frame in the form illustrated is provided with suitable doors for the food and ice compartments. The door 26 of the ice compartment is shown in place and closed, while the other doors, not shown, are to be fitted to the remaining openings.

This front frame is shown as built up of suitable wooden members 27 rigidly secured together in the usual manner. Preferably the frame on the rear face is provided with vertical reinforcing wooden members 28. 105 The interior of the cabinet may be insulated in any suitable manner as by the insulator 29 and interior casing 30.

The completed sheet metal enamel lining is secured to the front frame and clamped thereto so as to bring the flanges of the various plates in close contact therewith, producing tight joints and a pleasing effect. For this purpose clamping connections are secured to the side walls of the plates and to the front frame so that, when these clamping connections are drawn up, the flanges are clamped firmly against the rear surface of the frame. This arrangement enables the flanges to give or yield slightly and make the desired fit. These clamping connections may be located at suitable positions on the lining, and each is shown as comprising an angle plate 31, the longer arm of which is secured to the lining plate as by a bolt 32, and the shorter member of which is provided with a hole 33 through which a screw 34 passes into the frame. This angle plate is set back from the rear face of the frame so that, when the screw 34 is tight-

ened up, the flange of the lining plate may be pulled up snugly against the frame. In order not to damage or injure the lining, the bolts 32 are preferably in most cases part 5 of the studs which support the shelves in the food closets. These studs 35 are screwed to the inner end of the bolts against the opposite face of the lining. But where no shelf is employed, as in the lower left hand food 10 compartment, a short cap or stud 36 may be employed.

The front frame is filled in at the front of the bottom plate with a strip 37 of wood and the flange 3 of the bottom plate is 15 clamped up against this strip by a clamping strip 38, held in place by screws 39 so as to give a tight joint at the bottom.

If desired, finishing strips 40 of wood or other suitable material may be placed at the 20 edges of the door openings of the frame and provided with inward beveled edges abutting the flanges of the lining plates, and these strips may be drawn tightly in place by nails 41.

Having thus described my invention, what I claim as new, and desire to secure 25 by Letters Patent, is:

1. An L shaped sheet metal cabinet lining comprising a bottom plate having a flange 30 at its front edge, a long and a short side plate extending upwardly from the bottom plate, a top plate extending laterally from the long side plate, and intermediate partition plate extending downwardly from the 35 top plate with its body portion terminating well above the bottom plate, an L shaped back plate connecting the top, bottom, side, and partition plates, and a hollow vertical post connecting the lower front corner of the 40 partition plate and the bottom plate, the bottom plate having an aperture therethrough at the post interior, whereby the lower front corner of the partition plate is rigidly held in position and distortion of the 45 bottom plate in the vicinity of its junction with the post is precluded when the lining is heated as in an enameling process.

2. An L shaped sheet metal cabinet lining having the construction defined in claim 50 1 in which the hollow vertical post is provided with an extended longitudinal opening.

3. A sheet metal cabinet lining comprising in its structure a flat metal plate having 55 a flange along one edge and an aperture in the plate adjacent the flanged edge and a hollow sheet metal post permanently secured to and projecting from said plate around the edge of said aperture, whereby 60 distortion of the plate is precluded when the structure is submitted to intense heat as in an enameling operation.

4. A cabinet comprising a casing having a front frame, a sheet metal lining having 65 transversely flanged front edges, and clamp-

ing means connecting the side walls of the lining to the front frame, whereby the flanged edges of the lining may be drawn up tightly against the frame.

5. A cabinet comprising a casing having 70 a front frame, a sheet metal lining having vertical walls presenting transverse flanges, shelf supporting studs mounted in and passing through said walls, and clamping connections secured to said studs and to said frame and acting, when drawn up, to hold the flanges tightly against the frame.

6. A cabinet comprising a casing having 75 a front frame, a sheet metal lining having vertical walls presenting reentrant front sections provided with transverse flanges, shelf supporting studs mounted in and passing through said walls, and clamping connections secured to said studs and to said frame and acting, when drawn up, to hold 80 the flanges tightly against the frame.

7. A sheet metal cabinet lining comprising 85 a bottom plate having a flange at its front edge, a vertical plate having its body portion terminating well above the bottom plate, a hollow vertical post connecting the lower front corner of the vertical plate and the bottom plate, the bottom plate having 90 an aperture therethrough at the post interior, whereby the lower front corner of the vertical plate is rigidly held in position with respect to the bottom plate and distortion of the bottom plate in the vicinity of its junction with the post is precluded when 95 the lining is heated as in an enameling process.

8. A sheet metal cabinet lining comprising 100 a bottom plate having a flange along its front edge, a vertical plate having its body portion terminating well above the bottom plate and provided at its front edge with a flanged portion extending down to the bottom plate, a hollow vertical post comprising in its construction the said extended 105 flanged portion of the vertical plate and therewith connecting the lower front corner of the vertical plate and the bottom plate, the bottom plate having an aperture therethrough in line with the post interior and in the rear of the front edge flange, whereby the lower front corner of the vertical plate is rigidly held in position and distortion of the bottom plate in the vicinity 110 of its junction with the post is precluded when the lining is heated as in an enameling process.

9. An L shaped sheet metal cabinet lining comprising an integral bottom plate, a long and a short side integral plate extending upwardly from the bottom plate, an integral top plate extending laterally from the long side plate, an intermediate integral partition plate extending downwardly from the top plate with its body portion terminating well above the bottom 115 120 125 130

plate, an integral L shaped back plate connecting the top, bottom, side, and partition plates, the unsupported edges of said plates being provided with rigid stiffening flanges and the meeting edges of the said plates being permanently welded together, and a rigid vertical post connecting the lower front corner of the partition plate and the bottom plate.

10 10. An L shaped sheet metal cabinet lin-

ing comprising the construction defined in claim 9, together with a temporary brace connecting the upper front edge of the short side plate and the said post to prevent distortion of the said side plate.

15

In testimony whereof, we have signed our names to this specification.

FESSENDEN C. AMES.
HARRY L. MERRILL.
